UNITED STATES PATENT OFFICE.

VINCENT E. GREGG, OF CLEVELAND, OHIO, ASSIGNOR OF ONE-HALF TO
EDWARD F. BOHM, OF SAME PLACE.

JOIST AND WALL HANGER.

SPECIFICATION forming part of Letters Patent No. 546,147, dated September 10, 1895.

Application filed May 24, 1895. Serial No. 550,488. (No model.)

To all whom it may concern:

Be it known that I, VINCENT E. GREGG, a citizen of the United States, residing at Cleveland, in the county of Cuyahoga and State of Ohio, have invented certain new and useful Improvements in Joist and Wall Hangers; and I do hereby declare the following to be a full, clear, and exact description of the invention, such as will enable others skilled in the art to which it appertains to make and use the same.

My invention relates to improvements in joist and wall hangers, its object being to improve the construction and simplify the manufacture of the hangers; and it consists in the novel construction, arrangement, and combination of parts to effect such object, as hereinafter fully described, and pointed out in the claim.

20 In the drawings, Figure 1 is a diagram showing the manner of cutting and bending the blanks to form my improved hanger. Fig. 2 represents the completed hanger in face or front elevation. Fig. 3 represents the same in side elevation, and Fig. 4 in rear elevation. Figs. 5, 6, and 7 are top plan views of the hanger, illustrating various slight modifications of structure to adapt the hanger to special uses. Fig. 8 is a diagram showing in side 30 elevation the effects of strain upon a joist-hanger and illustrating some of the effects of my improvement in hangers.

Heretofore hangers have been made of various forms of rod or sheet metal and adapted to be secured to the supporting-beam, either by hooking over the top, as in the patent to L. M. Ham, No. 247,050, dated September 13, 1881, or by having a lug on the hanger inserted into a hole bored in the supporting-beam, as in the patent to W. Reuschel, dated October 29, 1889, No. 414,169.

In the hangers made of rod an objectionable feature is found in the necessity for notching or recessing the joist or flooring to accommodate the thickness of the hanger, while in those which are inserted into holes bored in the supporting-beam an equally objectionable feature is their weakening of the supporting-beam and rendering it liable to split.

The foregoing and all other objections are

obviated by my invention and construction of hanger, which is made from moderately thin plate or bar metal, and having an equal thickness and cross-section throughout, as shown, 55 does away with the necessity for notching or cutting any of the parts in contact with it and presents an equal resistance and strength throughout.

Referring to the drawings, *a* represents the 60 step or seat of the hanger; *a'*, the sides or cheeks; *b*, the wings or face-webs extending from the front edge or toe of the seat to the top or front edge of the supporting part; *c c*, the supporting parts turned back at right angles to the back of the cheeks *a'*, which rest against the side of the supporting-beam, and *c'* the downturned lugs which engage the supporting-beam, either by fitting down behind it or being driven down into its top, as may 70 be preferred. This construction of hanger has the advantage, among others, that it can be made without waste from ordinary commercial bar-iron, and does not require the use of specially rolled or prepared metal. The bar— 75 such, for instance, as two and one-half by three-sixteenths flat bar—is cut into lengths, as indicated by the full lines at *f f* in Fig. 1, and the blanks are bent along the lines *g g* *h h* *k k m m*, each bend being a right-angle bend 80 bringing the blank in but three bends into the completed form. (Shown in Figs. 2, 3, and 4.) Should it be deemed necessary in special cases to provide for fastening the hanger to the joist or supporting-beam, or both, a lug *d* may be 85 struck up from the seat *a*, which will enter the joist and hold it in place, and similar lugs *e e* may be struck down from the parts *c c*, so as to enter the supporting-beam and fasten the hanger securely thereto. When the hanger 90 is to be used as a wall-hanger, the lugs *e* may be increased in number, or preferably the parts *c c* may be left without the downturned lips *c'* and provided with corrugations *w w*, as seen in Fig. 7.

95 In the use of joist-hangers there is always a tendency of the hanger to draw away from the supporting-beam at the top, which is due to the fact that the weight of the joist themselves, particularly if long, have a tendency 100 to sag in the middle, which brings the greatest weight on the toe or front edge of the seat, and

to an equal extent relieves the weight on the back of the seat, as is illustrated in Fig. 8, in which the arrow shows the direction of the strain, the full lines show the normal position of the joist, hanger, and supporting-beam, and the dotted lines indicate the position into which the joist and hanger are brought by the action of load placed upon the joists. This tendency of the hanger to pull away from the supporting-beam at the top is sometimes opposed by bolting the top of the hanger to the beam, which expedient causes increased expense and labor as well as still further weakening the beam, whereas by my improved hanger the load which bears on the toe of the hanger is transmitted through the wings *b b* directly to the top of the beam and is at all points resisted by the full section of the hanger, while in most hangers the sectional area of the hanger becomes less and less as the top or point of attachment is neared. Other advantages of my improved form of hanger are its light weight as compared with other hangers of equal strength; no punching, driving of spikes, boring or fitting is required; no specially-prepared material is required; no waste in manufacture; simplicity

of machinery required, owing to all the bends being at right angles; its unusually wide bearing on the girder or supporting-beam distributes the load more uniformly on the latter; the joist bears directly against the girder or supporting-beam from bottom to top and gives no opportunity for the latter to twist, and, finally, it can be applied more quickly than any other form of hanger.

What I claim as my invention, and desire to secure by Letters Patent, is—

A joist hanger having a seat for the joist, side-pieces extending therefrom to the supporting parts, and decreasing in width from the seat to the top, supporting wings extending from the toe of the seat to the top and increasing in width to an extent proportionate to the decrease in width of the side pieces, and a supporting part in continuation at right angles of each wing and adapted to rest on the supporting beam, substantially as described.

In testimony whereof I hereto affix my signature in presence of two witnesses.

VINCENT E. GREGG.
